DESIGN FOR AN ANTI-THUMB-SUCKING DEVICE

Robert Parke, Buffalo, N. Y.

Application April 15, 1933. Serial No. 47,797

Term of patent 14 years

To all whom it may concern:

Be it known that I, ROBERT PARKE, a citizen of the United States of America, residing at the city of Buffalo, in the county of Erie and State of New York, have invented a new, original, and ornamental Design for Anti-Thumb-Sucking Devices, of which the following is a specification, reference being had to the accompanying drawing, forming a part thereof.

In the drawing Fig. 1 is a perspective view, Fig. 2 is a plan view, and Fig. 3 is a side elevation showing my new design.

I claim:

The ornamental design for an anti-thumb-sucking device as shown.

In testimony whereof, I have hereunto signed my name.

ROBERT PARKE.
